UNITED STATES PATENT OFFICE.

JOSEPH P. YOUNG, OF MARSHALLTOWN, IOWA, ASSIGNOR OF THREE-FOURTHS TO W. L. PECKHAM, C. F. SMITH, AND J. F. HARRIGAN, OF MARSHALLTOWN, IOWA.

JAR CLOSURE AND FASTENER.

SPECIFICATION forming part of Letters Patent No. 784,509, dated March 7, 1905.

Application filed June 13, 1904. Serial No. 212,381.

To all whom it may concern:

Be it known that I, JOSEPH P. YOUNG, a citizen of the United States, residing at Marshalltown, in the county of Marshall and State 5 of Iowa, have invented certain new and useful Improvements in Jar Closures and Fasteners; and I do declare the following to be a full, clear, and exact description of the invention, such as will enable others skilled in the 10 art to which it appertains to make and use the same.

My invention relates to improvements in jar closures and fasteners; and it consists in the construction, combination, and arrangement 15 of devices hereinafter described and claimed.

In the accompanying drawings, Figure 1 is a side elevation showing the upper portion of a jar, a closure, and fastening devices embodying my improvements. Fig. 2 is a sectional view of the same, taken on the plane indicated by the line *a a* of Fig. 1. Fig. 3 is a top plan view of the same.

The jar 1 is of the usual form and has a 25 bail 2 pivotally connected thereto, as at 3. On the bail is a lever 4, fulcrumed thereto and slidably thereon. The lever has a slot 5 near one end, through which the bail extends and is provided at the said end with a 30 foot 6, the ends of which project from opposite sides of the lever.

The closure or cover 7 has a flange 8 to bear on the mouth of the jar and a rubber or other suitable gasket 9 to effect a tight connection therewith.

The cover is formed with a central boss 10, which projects from its upper side. A channel 11 is cut transversely across the upper side of the boss, at the center thereof, to 40 form a pair of flanges 12. The latter at their centers on their upper sides are provided with shallow notches 13. Their ends are stepped or notched, as at 14. Across the center of the channel extends a shoulder 15, and on opposite sides of the base of the shoulder the channel is provided with notches or 45 depressions 16.

The slot with which the lever is provided enables said lever to be moved to some extent in the direction of its own length on the 50 bail.

To secure the cover on the jar, the bail is moved over the cover to an inclined position and the foot of the lever engaged with one of the notches or depressions 16 in the bottom 55 of the channel 11. This disposes the lever also in an inclined position, as shown in dotted lines in Fig. 2. The lever is then turned in the direction indicated by the arrow in said figure, its foot forming its fulcrum, and 60 the lever thereby raises the center of the bail, which forms a spring, moves the same to a vertical position, and seats the bail in the notches or depressions 13 in the centers of the flanges 12, thereby effectually securing 65 the cover on the jar. The foot of the lever then disengages the channel, and the lever assumes the position shown in full lines in Fig. 2 and hangs loosely from the bail. To open 70 the jar, the lever is moved in the reverse direction, reseating its fulcrum-foot in the notch or depression 16, disengaging the bail from the notches or depressions 13, and swinging the bail clear of the flanges of the boss, hence releasing the cover, as will be understood. The construction of the cover is 75 such that the lever may be employed to engage the bail with the notches 13 from either side of the boss.

Having thus described my invention, what 80 I claim as new, and desire to secure by Letters Patent, is—

1. In combination with a jar and a bail, a lever pivotally connected to the bail, and a cover having a central boss on its outer side, 85 provided with flanges, notched in their outer edges, said cover being further provided with a channel between said flanges, a centrally-disposed shoulder extending across the channel, and notches in the bottom of the channel on opposite sides of the base of the shoulder, for engagement by one end of the lever, substantially as described.

2. In combination with a jar and a bail, a

lever connected to the bail and having one end provided with a fulcrumed foot forming a lateral extension thereof, and a cover having a central boss on its outer side, provided with flanges, notched in their outer edges, said cover being further provided with a channel between said flanges, a centrally-disposed shoulder extending across the channel, and notches in the bottom of the channel, on opposite sides of the base of the shoul-

der, for engagement by the fulcrum-foot of the lever, substantially as described.

In testimony whereof I have hereunto set my hand in presence of two subscribing witnesses.

JOSEPH P. YOUNG.
